UNITED STATES PATENT OFFICE.

JOHN J. BROWNRIGG, HARRY HENDERSON, AND ARTHUR E. CASE, OF MARION, INDIANA,
ASSIGNORS TO, DELTA ELECTRIC COMPANY, OF MARION, INDIANA, A CORPORATION
OF INDIANA.

COIN-COLLECTOR FOR TELEPHONE SYSTEMS.

1,205,150.

Specification of Letters Patent. Patented Nov. 21, 1916.

Application filed January 26, 1914. Serial No. 814,588.

To all whom it may concern:

Be it known that we, JOHN J. BROWNRIGG, HARRY HENDERSON, and ARTHUR E. CASE, residents of Marion, in the county of Grant and State of Indiana, have invented new and useful Improvements in Coin-Collectors for Telephone Systems, of which the following is a full, clear, and exact description.

10 The invention relates to coin-collectors for telephone systems.

One object of the invention is to provide an improved coin-collector which is adapted to receive coins of different denominations 15 and to signal the deposit of the same to the exchange-office.

Another object of the invention is to provide improved inimitable coin-controlled electrical signaling means whereby the 20 change-operator will be notified of the deposit of a coin and the denomination thereof.

A further object of the invention is to provide improved coin-collecting apparatus which is locked against release except by a 25 coin of a proper denomination.

Other objects of the invention will be manifest from the apparatus hereinafter set forth.

The invention consists in the several novel features hereinafter set forth and more particularly defined by claims at the conclusion hereof.

In the drawings: Figure 1 is a diagrammatic view of a telephone system and its electrical connections with the coin-collector. 35 Fig. 2 is a plan view of the coin-collector, the inclosing case and the supporting frame therein being shown in section. Fig. 3 is a front view of the coin-collector, the case being shown in section. Fig. 4 is a side elevation, the case being shown in section. Fig. 5 is a front elevation, the inclosing case being shown in section and the refunding chute being removed. Fig. 6 is a transverse section taken on line 6—6 of Fig. 5, the parts 45 being shown in position assumed when a coin has been deposited, but before the coin-shifter has been operated to actuate the signaling-mechanism. Fig. 7 is a section taken on line 7—7 of Fig. 6. Fig. 8 is a transverse section taken on line 8—8 of Fig. 3, the parts being shown in position assumed when the coin-shifter has been pushed rearwardly 50 to deposit a coin to operate the signaling-

mechanism. Fig. 9 is a section taken on line 9—9 of Fig. 3, parts being shown in normal position. Fig. 10 is a side elevation opposite to that shown in Fig. 4, the inclosing case being shown in section.

The sub-station toll-collecting apparatus comprises a back plate 12, on the lower portion of which, a coin compartment 14 is formed. An inclosing case 15, which is secured to the back-plate on top of the coin-compartment, serves to inclose the operating-mechanism of, and the connections for, the collector. The apparatus illustrated is adapted to receive coins of three denominations and the case 15 is provided with coin-slots 16 through which coins may be deposited in payment of toll, there being a separate slot for coins of each denomination. A supporting frame 17 comprising sides 18 and 19, is secured to the back plate 12 by screws 12'. The operating parts of the collector are sustained by frame 17.

Coin-channels for directing the deposited coins to a coin shifter 20, are formed between a pivoted wall 21 and a cross-wall 22 which is fixed to the sides of frame 17. Wall 21 is pivoted on a cross-rod 22' which is secured in frame-sides 18, 19. Lugs 23 on pivoted wall 21 serve as guides for directing the coins deposited into slots 16, into corresponding pockets 25 formed in the coin-shifter 20, respectively. Shifter 20 is secured to a push-rod 26 which is slidably mounted in the guides 27 on frame-side 18 and the shifter is adapted to slide with said rod. A spring 28 serves to retract the shifter. The push-rod 26 extends through the front of case 15 so that it can be pushed inwardly by the depositor. A lug 29 on the shifter 20, through which rod 26 extends and to which it is secured, is adapted to engage the front guide 27 in frame-side 18 to arrest and normally hold the shifter in position to receive the deposited coins from the channels between plates 21 and 22. This coin-shifter serves to move the coins to a point above a channel or duct 30 so that they will be discharged into the coin-compartment 14. A stationary table or plate 31, having ribs 32 thereon, is disposed under the coin-shifter to retain the coins in the pockets in the shifter until the shifter has been moved to a point in back

of the table and over duct 30. As the coins in the shifter are moved backwardly, they operate the signaling mechanism to notify the operator of their deposit and the denomination of the coins.

To prevent deposit of one coin before a previously deposited one has been displaced and has operated the signaling mechanism, provision is made for refunding any coins that may be deposited while a coin is suspended in the coin-shifter. For this purpose, the pivoted gate 21 is provided with arms 33 which normally extend into the pockets in the coin-shifter and which will be engaged by a coin in any of the pockets respectively, to hold wall 21 (Fig. 6) into position to prevent coins, deposited through any of the slots 16, from passing into the coin-channels between plates 21 and 22. It 26 a coin should be deposited through any of the coin-slots while the pivoted wall 21 is closed against wall 22, such coin will be deflected by wall 21 and will fall into a refunding-chute 34 and be conducted to a refunding-cup 35. To keep the coin-channels between walls 21 and 22 closed, to cause coins to be refunded during the transit of the coin and while the coin-shifter is out of its normal position, a spring 36, which is secured to the wall of the refunding-chute 34, is normally held away from an abutment 37 on pivoted wall 21 by a lug 38 on the coin-shifter, so that while the shifter is in normal position, the pivoted wall will be 30 free to be shifted by a coin engaging one of the arms 33 and when the shifter is pushed backwardly, lug 38 will release spring 36 so it will bear against lug 37 on deflector-plate 21 and hold said plate closed until the coin-shifter has been restored to its normal position.

One object of the invention is to dispense with the use of audible signals at the substation which are transmitted through the transmitter and over the line by means of a resonant connection between the signaling device and the transmitter. For this purpose, mechanism is provided for characteristically opening and closing a signaling circuit at contacts 41 and 43 to signal the deposit of a coin to the exchange-operator and to indicate the denomination of the coin deposited. In the machine shown as an exemplification of the invention, a twenty-five cent coin is adapted to cause said contacts to be operated three times; a dime is adapted to operate the contacts twice, and a five-cent piece is adapted to operate the contacts once, thus signaling to the exchange the denomination of the deposited coin. Contact 41 is resilient and is operated so it will be caused to vibrate by mechanism hereinafter set forth to produce a distinctive signal and one clearly distinguishable from an ordinary make-and-break of the

circuit. This sort of a signal is difficult of simulation. Contacts 40 and 41 are held normally closed and contact 40 is limited in its movement toward contact 41 by a stop-strip 42. Stop-screw 43 is provided for contact 41. This stop screw is disposed adjacent the fixed end of resilient contact-strip 41 so that the contact point on said strip will be free to vibrate adjacent the contact 40 as the contact 41 is released. The contacts 40 and 41 are insulated from each other and are secured to a lug 44 on frame-side 19.

An escapement wheel 45 is mounted to rotate on a shaft 46 which is journaled in the supporting frame 17 and the teeth of said wheel are pointed and formed so that they will alternately strike and release the strip of insulation 47 on contact-strip 41 which will be alternately pressed against contacts 40 and 43 and release to vibrate in proximity to contact 40 and produce a peculiar signal.

Mechanism is provided for rotating the escapement wheel 45 according to the denomination of the coin deposited. Shaft 46 has secured thereto, three arms 48 for the coins in the coin-pockets in shifter 20. These arms are so disposed and of such length that each will be shifted by coins of the proper denomination, respectively, one or more steps according to the denomination of the coin. Normally, these arms are disposed in the path of the coins in the coin-shifter 20 and are adapted to be swung upwardly by the coins to rock shaft 46. Coin-shifter 20 is cut away, as at 50, to permit the coins to engage arms 48 and to permit the shifter to pass under said arms when no coin is present. A lever 51 is secured to one end of shaft 46, and is provided with an arm 52, which is adapted, when in normal position (Fig. 4), to engage the insulating strip 47 on contact 41 to firmly hold said contact against contact 40 and to break the circuit between contacts 43 and 41. Lever 51 is also provided with an arm 53 which carries a pawl 54 for stepping up the escapement wheel 45 according to the denomination of the coin deposited. Pawl 54 is pivoted, as at 55, to the outer end of arm 53, and is normally held in one-way engagement with the escapement wheel 45 by a spring 56. Lever 51, being secured to shaft 46 to which the coin-shifted arms 48 are secured, will be shifted in one direction by a coin in the coin-shifter 20. This movement may vary according to the force applied by the depositor to the push-rod 26, and to overcome variation in and prevent too rapid operation of the escapement-wheel during the signaling operation, pawl 54 slips over the teeth on escapement wheel 45 when the coin is manually shifted and the lever 51 is shifted by a coin, and the retractile move-

ment of the lever effected by a spring 56' applied to shaft 46, is utilized to uniformly step up the escapement wheel 45. To regulate the movement of escapement-wheel 45 so that there will be sufficient pauses between the operations of contact 41 to distinguish the impulses or signals from one another, an escapement dog 57 has teeth 58 and 59 which are adapted to alternately engage the teeth of the escapement-wheel 45 and retard the stepping-up movement of said wheel by the pawl 54 and lever 51. Dog 57 is secured to a cross-shaft 60 which is journaled in the frame 17 and has a retarding or fly-wheel 61 secured thereto. This wheel and the dog, which must be vibrated as the escapement-wheel 45 is stepped up, thus serve to regulate the retraction of lever 51 and the operation of the escapement-wheel, to time the spaces between the impulses, caused by the making and breaking of the circuit at contacts 43 and 41.

The escapement-wheel 45 is normally locked against movement in either direction by a locking-dog 63 which engages with escapement 45 which is secured to a short shaft 64 which is journaled in the frame-side 19 and said dog is normally held to lock the wheel by an arm 65 on lever 51 which engages a lug 66 on said dog. Resultantly, there can be no movement of the escapement-wheel 45 while lever 51 is in its normal position.

Dog 63 is locked into engagement with the escapement-wheel by a hook 68 on the end of an arm 69 which is pivoted to the frame-side 19, at 70, and is provided with an abutment 71 adapted to be engaged by the back of the coin-shifter 20 to swing hook 68 away from a stud 72 which projects inwardly and is secured to dog 63. Resultantly, no signaling can be effected by escapement-wheel 45 until the coin-shifter has been operated a full stroke. A spring 74, connected to dog 63 and to arm 69, serves to lift dog 63 out of engagement with the escapement-wheel 45 when the hook 68 is operated to release the dog and lever 51 has been shifted to cause arm 65 to release lug 66, the force of spring 74 being insufficient to overcome the force applied to lever 51 by spring 56'. When dog 63 has been raised, which occurs after a coin has shifted lever 51 and the coin-shifter has struck abutment 71 on arm 69, the side of hook 68 will rest on stud 72 and be held so that the arm 69 will not be restored to normal position and operative to lock dog 63 until lever 51 has completed its full retractile stroke, and arm 65 has engaged lug 66 on dog 63 and shifted the latter into locking position. Resultantly, the escapement-wheel which effects the signaling cannot be operated unless lever 51 has been operated by a coin in the shifter 20 and the shifter with the coin therein has

been shifted to discharge the coin into the cash-compartment.

In Fig. 1, the improved signaling device is shown connected to a telephone-system of usual construction. The central exchange 70 A is provided with the usual cord-loop *a* terminating in an answering plug *g* and a calling plug *h*. The equipment at the exchange comprises the usual listening-key *n* and an operator's telephone-set comprising 75 a transmitter *T* and receiver *R*, supervisory signals *m*, *m'*, supervisory-relays *l*, *l'*, and a battery *a'*, all suitably connected together in manner well understood in the art. The exchange equipment also comprises a spring-jack *b*, a line-signal *c*, a line-signal relay *d* and a cut-out relay *e* which are connected to the line-conductors *f*, *f'*, in the usual manner.

The equipment at the sub-station 85 comprises a receiver 80, transmitter 81, a switch-hook 82, and a ringer 83 which are connected to the line-conductors, as shown, and as well understood in the art.

Line-conductor *f'* is connected by a 90 branch-conductor 84 to spring-contact 40 and contact 41 is connected by a conductor 85 to line-conductor *f*. A branch-conductor 86, connects contact-screws 43 to the line-conductor *f'*. Contact 41 is connected by 95 conductor 85 to line-conductor *f* to which the primary coil *I* and a transmitter 81 are connected by conductor 87 and which terminates in a contact at the switch-hook 82. Switch-hook 82 is connected to the line-conductor *f'*, and when the hook is raised, conductors 87, 85, will be included in the circuit for speech-transmission when 41 contacts with 43. When switch-hook 82 is raised, the line will be closed at the switch- 100 hook and current from the exchange passing over line-conductor *f* will pass through transmitter 81, primary coil 88, conductors 87, 85, conductor 86 and line-conductor *f'* back to the exchange. When the resilient 105 contact 41 is vibrated by the escapement-wheel 45, it will, by reason of its own resilience, vibrate rapidly between contact 43 and spring 40, producing a characteristic signal which will be transmitted over the 110 telephone-line to the operator's telephone set at the exchange, in manner well understood in the art, the operator's telephone-set being at that time connected to the line in the usual manner.

The operation of the toll-collector will be as follows: When the patron removes the receiver 80 from the switch-hook 82, the line signal at the exchange will be actuated in usual manner, and when the exchange-operator inserts the switch-plug *g* into the spring-jack *b* and operates the listening key *n* to connect her set with the calling sub-station, connection for speech-transmission will be established between the exchange op- 115 120 125 130.

erator and the patron at the sub-station, so that the exchange-operator may ascertain the connection desired. When the exchange-operator has ascertained that the desired service can be given, the patron is directed to deposit a coin or coins, singly into the collector. When a coin is deposited through one of the coin-slots 16, it will fall into the channel between plates 21 and 22 and be guided thereby into one of the subjacent pockets in the coin-shifter 20, as shown in Fig. 6, being held therein by table 31. The coin, in passing into the shifter, will strike one of the arms 33 on pivoted plate 21 and swing the upper end of this plate into position to close the coin-channels between plates; whereupon any further coin deposited into either of the slots 16 will fall into the refunding-channel at the front of plate 21 and be discharged into the refunding-cup 35. The depositor will next push the plunger 26 inwardly, which will cause the coin suspended in the coin-shifter to move backwardly under and to lift one of the arms 48 on shaft 46, and after it has shifted said arm, and is moved off table 31, it will fall through channel 30 into the cash-drawer. The rotation of shaft 46, resulting from engagement of the coin with one of the arms 48, will cause arm 52 on lever 51 to be operated to release contact 41 and its insulating strip 47 so that said contact will spring away from contact 40 and into the path of the teeth of escapement wheel 45. Such operation of lever 51 will also move escapement-operating pawl 54 backwardly and move arm 65 away from lug 66 on locking-dog 63. The extent of shift of the lever and rotation of shaft 46 are determined by the denomination of the coin which has been deposited. Lever 51 will remain in the position to which it is shifted by the coin until sufficient backward movement has been imparted to the coin-shifter to discharge the coin. At the end of its inward or backward movement, the coin-shifter 20 will strike abutment 71 on the locking arm 69 and swing hook 68 backwardly to release stud 72 on the locking dog 63, whereupon spring 74 will cause dog 63 to swing upwardly clear of the escapement-wheel 45. Thereupon, the retracting spring 56', under the regulation of the escapement-dog 57 and the fly-wheel 61, will operate lever 51 to operate escapement-wheel 45 by means of pawl 54. As each tooth of escapement-wheel 45 rides over the insulating strip 47 on contact 41, it will alternately press said contact against contact 40, and then release contact 41 so its inherent resiliency will vibrate it. If the escapement wheel has been shifted a distance corresponding to three teeth by a coin, it will produce three separate signals by operating the contact 41 three times. When the lever 51 reaches its normal position, arm

52 will press against strip 47 and force contact 41 firmly against contact 40 to cause the circuit for speech-transmission to be kept closed at said contacts. Simultaneously, arm 65 on lever 51 will engage lug 66 and force dog 63 into engagement with the escapement-wheel 45 and lock the latter against rotation.

The invention thus provides coin-controlled mechanical means for vibrating an electrical contact to produce a distinctive signal which cannot be simulated by an ordinary making and breaking of the line-circuit; also an improved toll-apparatus which is adapted to receive coins of different denominations and to indicate the denomination thereof to the exchange-operator; also mechanism for causing the signal-operating device to operate regularly and without being varied by rapid or slow operation of the coin-shifting apparatus; and also a toll-collector which need not be secured to or movable with the sub-station telephone-set, because a resonant connection for conducting the signals to the sub-station transmitter is not used.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. In toll collecting apparatus for telephones, the combination of signaling means, a toothed wheel adapted to operate the signaling device by consecutive shifts in the same direction, coin-controlled means for rotating the wheel in one direction only, and means for constantly preventing rotation of the wheel in the opposite direction.

2. In a toll-collecting apparatus for telephones, the combination of a switch for controlling a signaling circuit, a toothed wheel for mechanically vibrating a member of said switch, said wheel being adapted to operate said member by consecutive shifts in the same direction, and means for constantly preventing rotation of the wheel in the opposite direction.

3. In toll collecting apparatus for telephones, the combination of a switch for controlling a signaling circuit, a toothed wheel for mechanically vibrating a member of said switch and having means to operate said member by consecutive shifts in the same direction, coin-controlled means for operating the wheel in one direction and means for constantly preventing rotation of the wheel in the opposite direction.

4. In a toll collecting apparatus for telephones, the combination of signaling means, coin-controlled mechanism for operating said signaling means, an escapement device

for controlling the operation of the signaling means, comprising a dog and a shaft, and a fly-wheel connected to said shaft.

5. In toll collecting apparatus for telephones, the combination of signaling means, a wheel having teeth thereon to operate the signaling means by consecutive movements in one direction, a coin-shifter, mechanism operable by a coin in the shifter for operating said wheel in one direction, means for constantly locking the wheel against rotation in the reverse direction, and means for normally locking the wheel against rotation in the first mentioned direction, operable by 10 the shifter.

6. In toll collecting apparatus for telephones, the combination of a signaling device, coin-controlled means for operating said device, a refunding channel in the case, 20 a coin deflector for diverting a coin into the refunding channel, and means for operating the deflector when a coin is deposited to direct a coin into the refunding channel when the coin-controlled operating means is in an 25 abnormal position.

7. In toll-collecting apparatus for telephones, the combination of a signaling device, coin-controlled means for operating said device, a case having coin-receiving 30 slots therein, a refunding channel in the case, a pivoted coin-deflector, a fixed wall coöperating with said deflector to guide the coin to said coin-controlled means, and means for operating the deflector when a 35 coin is deposited to direct a second coin into the refunding channel.

8. In toll-collecting apparatus for telephones, the combination of a signaling device, a case having a coin-receiving slot 40 therein, a coin-deflector in the case, a coin-shifter, mechanism operated by a coin in the shifter for operating the signaling device, the case having a refunding channel therein, and means for causing the deflector 45 to deflect the coins into the refunding-channel when the shifter is out of its normal coin receiving position.

9. In toll-collecting apparatus for telephones, the combination of a signaling device, a case having coin-receiving slots 50 therein, a coin-shifter in the case, mecha-

nism operated by a coin in the shifter for operating the signaling device, the case having a refunding channel therein, a deflector, means on the deflector for causing it to be 55 shifted by a coin to deflect a second coin into the refunding channel, and a spring for holding the deflector in position to refund coins when the shifter is out of its normal coin-receiving position. 60

10. In toll-collecting apparatus for telephones, the combination of a signaling-device, a case having coin-receiving slots therein, a coin-shifter in the case, mechanism operated by a coin in the shifter for 65 operating the signaling device, the case having a refunding channel therein, a pivoted deflector wall, a fixed wall coöperating with said pivoted wall to guide coins to the shifter, means on said pivoted wall for 70 shifting the deflector when a coin is deposited to deflect a second coin into the refunding channel, and a spring controlled by the shifter for operating said deflector to refund coins when the shifter is out of its 75 normal coin-receiving position.

11. In toll collecting apparatus for telephones, the combination of signaling means, a toothed wheel for operating the signaling means and rotatable in one direction only, 80 mechanism for imparting consecutive step by step movements to the wheel in said direction to operate the signaling means, and coin-controlled mechanism for operating 85 the stepping-up mechanism.

12. In toll collecting apparatus for telephones, the combination of signaling means, a toothed wheel for operating the signaling means, movable in one direction only, a lever and pawl for imparting consecutive step 90 by step movements to the wheel in one direction, coin-controlled means for operating the lever, and a lock for normally securing said wheel against rotation in its operative direction, and means operated by the lever 95 for releasing said locking means.
